GAME BOARD

Beverly Wright, Norwich, Conn.

Application December 11, 1952, Serial No. 22,620

Term of patent 14 years

(Cl. D34—5)

To all whom it may concern:

Be it known that I, Beverly Wright, a citizen of the United States of America, residing at Norwich, in the county of New London and State of Connecticut, have invented a new, original, and ornamental Design for a Game Board, of which the following is a specification, reference being had to the accompanying drawing, forming a part thereof.

Fig. 2 is an edge view of the game board.

I claim:

The ornamental design for a game board, as shown.

BEVERLY WRIGHT.
